JOHN ROBBINS ROSE AND EDWARD CALEY, OF PHILADELPHIA, PENNSYLVANIA,
ASSIGNORS TO SAMUEL B. SEXTON, OF BALTIMORE, MARYLAND.

Design No. 4,425, dated October 18, 1870.

DESIGN FOR A FIRE-PLACE STOVE.

The Schedule referred to in these Letters Patent and making part of the same.

We, JOHN ROBBINS ROSE and EDWARD CALEY, of the city and county of Philadelphia, in the State of Pennsylvania, have invented a new Design for Fire-place Stoves, of which the following is a specification.

Nature of the Invention.

Our invention relates to the conformation and ornamentation of the following parts of a fire-place stove and its appendages, to wit:

First, the external frame.

Second, the base-plate.

Third, the body of the stove, or walls of the combustion-chamber.

Fourth, the top rim.

Fifth, the intermediate rim surmounting the combustion-chamber walls.

Sixth, the center ornament between said rims.

Seventh, the ash-pit doors.

Eighth, the feeder.

Ninth, the water-vases.

Description of the Accompanying Photographs.

Figure 1 represents the front of the stove, rim, and feeder.

Figure 2 represents the external frame.

Figure 3 represents the base-plate.

Figure 4 represents a section of the stove-body or combustion-chamber walls.

Figure 5 represents the intermediate or second rim.

Figure 6 represents the ash-pit doors.

Figure 7 represents the feeder.

General Description.

The external frame, forming the first part of the invention, is shown at *a*, in figs. 1 and 2.

The base-plate, constituting the second part, is shown at *b*, in figs. 1 and 3.

The body of the stove or the walls of the main combustion-chamber are made up of a number of sections, shown at *c c c* in fig. 1. One of these sections is represented on a larger scale in fig. 4. This constitutes the third part of our invention.

The form and ornamentation of the top rim, constituting the fourth part of our invention, are clearly shown at *d* in fig. 1.

The intermediate rim, which forms the fifth part, is shown at *e* in fig. 1, and on a larger scale in fig. 5.

f, in fig. 1, represents the center ornament, the design of which constitutes the sixth part of the invention.

The ash-pit doors, constituting the seventh part, are shown at *g* in fig. 1, partially hidden by the fender *h*. They are clearly shown on a larger scale in fig. 6.

The fender is shown in perspective at *h* in fig. 1, and in front elevation in fig. 7. This forms the eighth part of our invention.

The ornamental water-vases, constituting the ninth part of the invention, are represented at *i i* in fig. 1.

Claims.

We claim as new in our design—

1. The form of the frame *a*, substantially as represented.

2. The form of the base-plate *b*, substantially as represented.

3. The form of the body *c* or walls of the combustion-chamber, substantially as represented.

4. The form of the top rim *d*, substantially as represented.

5. The form of the rim *e*, substantially as represented.

6. The form of the center ornament *f*, substantially as represented.

7. The form of the doors *g*, substantially as represented.

8. The form of the fender *h*, substantially as represented.

9. The form of the water-vases *i*, substantially as represented.

JOHN ROBBINS ROSE.
EDWARD CALEY.
